US0D1095864S

(12) **United States Design Patent** (10) **Patent No.:** **US D1,095,864 S**
(45) **Date of Patent:** **** Sep. 30, 2025**

(54) **BREAST PAD**

(71) Applicant: **Shenzhen Lute Jiacheng Supply Chain Management Co., Ltd., Shenzhen (CN)**

(72) Inventor: **Jialong Lu, Shenzhen (CN)**

(73) Assignee: **Shenzhen Lute Jiacheng Supply Chain Management Co., Ltd., Shenzhen (CN)**

(**) Term: **15 Years**

(21) Appl. No.: **29/913,157**

(22) Filed: **Sep. 27, 2023**

(51) LOC (15) Cl. **24-01**

(52) U.S. Cl.

USPC **D24/207; D24/124**
